UNITED STATES PATENT OFFICE.

FRANK H. STANWOOD, OF CHICAGO, ILLINOIS, ASSIGNOR TO STANWOOD EQUIPMENT COMPANY, OF CHICAGO, ILLINOIS, A CORPORATION OF MAINE.

DESIGN FOR AN AUTOMOBILE STEP-PLATE.

57,792.

Specification for Design.

Patented May 3, 1921.

Application filed October 24, 1919. Serial No. 333,130. Term of patent 14 years.

To all whom it may concern:

Be it known that I, FRANK H. STANWOOD, a citizen of the United States, residing at Chicago, in the county of Cook and State of Illinois, have invented a new, original, and ornamental Design for Automobile Step-Plates, of which the following is a specification, reference being had to the accompanying drawing, forming a part thereof.

On the drawing:

Figure 1 is a perspective view of an automobile step plate embodying my invention; and

Fig. 2 is an end view of the same.

I claim:

The ornamental design for an automobile step plate, as shown.

FRANK H. STANWOOD.

Witnesses:

T. J. O'BRIEN,
ETHEL WOOD.
